UNITED STATES PATENT OFFICE.

ORLANDO T. GRATTAN, OF IVANHOE P. O., COUNTY OF BROOKINGS, DAKOTA TERRITORY.

HAND CORN-PLANTER.

SPECIFICATION forming part of Letters Patent No. 268,220, dated November 28, 1882.

Application filed July 26, 1882. (No model.)

To all whom it may concern:

Be it known that I, ORLANDO TISDEL GRATTAN, of Ivanhoe P. O., Elkton Station, county of Brookings, and Territory of Dakota, have 5 invented a new and useful Improvement in Hand Corn-Planters, of which the following is a full, clear, and exact description.

Reference is to be had to the accompanying drawings, forming a part of this specification, 10 in which similar letters of reference indicate corresponding parts in all the figures.

Figure 1 is a side elevation of my improvement, partly in section. Fig. 2 is a front elevation of the same. Fig. 3 is a sectional plan 15 view of the same, taken through the line *xx*, Fig. 1.

The object of this invention is to facilitate the planting of corn, and also to promote convenience in operating hand corn-planters.

20 The invention consists in a hand corn-planter constructed with a seed-box having a seed-dropping slide operated by a hinged bar, with which is also connected by a bolt and spring the hinged jaw for dropping the seed. The 25 seed-box is provided with a spring-catch for holding the hinged bar, and which is operated to release the hinged bar by a cord connected with the pivoted handle of the planter, as will be hereinafter fully described.

30 A represents the seed-box, the front of which is extended upward, and has a rearwardly-projecting handle, B, pivoted to its upper end. The sides, front, and back of the seed-box A extend below its bottom, and the back 35 is made a little shorter than the other three parts.

To the inner side of the lower part of the back of the seed-box A is bolted the upper end of the rear jaw, C, which is inclined forward 40 to the central line of the said seed-box, and is then bent downward vertically.

The forward jaw, D, is hinged to a bolt, E, that passes through the sides of the seed-box about midway between its center line and 45 front and at a little distance from the lower ends of the said sides.

Through a hole in the upper part of the forward jaw, D, passes a bolt, F, which has two nuts, G, screwed upon it, about an inch apart, 50 and upon the opposite sides of the said jaw D, so that the said bolt and jaw will have a little play upon each other. The bolt F passes out

through a hole in the downwardly-projecting front plate of the said box A, and is attached to the inner edge of the bar H.

Upon the outer part of the bolt F is placed 55 a spiral spring, I, the inner end of which rests against the downwardly-projecting front of the seed-box A, and its outer end rests against the inner side of the bar H, so that the tension 60 of the spring I will force the upper part of the said bar H and the bolt F outward, and will draw the upper end of the jaw D forward, forcing its lower end against the jaw C. The lower end of the bar H is attached to the outer 65 part of a plate, J, the inner end of which is hinged to the lower edge of the downwardly-projecting front of the seed-box A.

To the forward side of the lower part of the bar H is secured a foot, K, by a bolt, L, with 70 its lower end projecting below the hinged plate J. The upper part of the foot K is slotted to receive the bolt L, so that the said foot can be adjusted by loosening the said bolt L.

The upper end of the bar H, when forced inward, is caught automatically and held by the catch M, which slides in keepers N, attached to the front of the seed-box A, and is held down by a spiral spring, O, placed upon it between the keepers N.

75 To the upper end of the spring-catch M is attached the end of a cord, P, which passes through a guide-hole in the upwardly-projecting part of the front of the seed-box A, and is attached to the pivoted handle B, so that the 80 catch M can be drawn upward to release the bar H by slightly turning the said handle B.

Q is the seed-dropping slide, which rests upon the bottom of the seed-box A and works 85 through cross-slots in the front and rear sides of the said seed-box A.

To the forward end of the slide Q is attached a loop, R, through which the upper part of the bar H passes, so that the seed-dropping slide 90 will be operated by the movements of the said bar.

In the slide Q is formed an aperture, S, to receive the seed, carry it out of the seed-box, and drop it into the spout T, down which it 95 slides into the space between the jaws C D. 100 The slide Q is slotted from its aperture S to its free end, and in the said slot is placed a strip, U, which is secured in place by a bolt, V, passing through the parts of the end of the

said slide, so that by loosening the bolt V the strip U can be adjusted to enlarge or contract the aperture S, according as more or less seed is required for a hill.

5 To the inner side of the front of the seed-box A is secured a brush, W, by a bolt, X, which passes through a hole in the brush W and a slot in the front of the seed-box, so that the said brush can be readily adjusted as required. The brush W is designed to keep the slide Q from becoming clogged by the seed getting into the slot in the front of the feed-box A, and is formed by clamping bristles between two metallic plates.

10 15 The seed conducting spout T is secured in an opening in the rear plate of the seed-box, just below the bottom of the said seed-box.

In using the planter the jaws C D, when close together, are forced into the soil to the proper depth. As the foot K comes in contact with the soil the upper end of the planter is forced forward, which forces the upper end of the bar H inward until it is caught and held by the catch M. The inward movement 20 25 of the upper end of the bar H opens the jaws C D and allows the seed to drop out into the opening made in the soil by the opening of the said jaws. As the planter is being raised from the ground the jaws C D are held open by the bar H and catch M, so that all the seed 30 35 will be left in the ground. As the planter is raised from the ground the operator turns the handle B, which raises the catch M, releases the bar H, draws the slide Q forward to again receive seed, and closes the jaws C, ready to be again thrust into the soil to plant another hill. Two hills can be planted at a time by connecting two planters together at the proper distance apart by one or more cross-bars. In 40 45 this case the handles B are replaced by a round pivoted to the upwardly-projecting fronts of the two planters, which round serves as a handle in carrying the planter, and to its middle part are attached the two cords P, so that the two catches M can be raised at the

same time by slightly turning the said round.

If desired, the loop R may be omitted and the connection between the slide Q and the bar H made by any suitable means.

Having thus described my invention, I claim 50 as new and desire to secure by Letters Patent—

1. A hand corn-planter constructed substantially as herein shown and described, and consisting of the seed-box A, the pivoted handle B, the stationary jaw C, the hinged jaw D, the bolt F, spring I, the hinged bar H, that operates the jaw D and the seed-dropping slide Q, and the spring-catch M O and its cord P, as set forth. 55

2. In a hand corn-planter, the combination, 60 with the seed-box A, the pivoted handle B, the hinged jaw D, and the seed-dropping slide Q, of the bolt and spring F I, the hinged bar H, the foot K, the spring-catch M O, and the cord P, substantially as herein shown and described, 65 whereby the hinged jaw and the seed-dropping slide will both be operated by the movements of the said hinged bar, as set forth.

3. The combination, with box A, slide Q, spring I, and loop R, of the angled bar H, 70 having the end of its short arm hinged to the bottom of box A, and a spring-held long arm connected with the said slide by the loop R, as shown and described.

4. In a hand corn-planter, the combination, 75 with the hinged jaw D and the hinged bar H, of the bolt F and spring I, substantially as herein shown and described, whereby the said jaw will be operated by the movement of the said hinged bar, as set forth. 80

5. In a hand corn-planter, the combination, with the spring-catch M O and the pivoted handle B, of the cord P, substantially as herein shown and described, whereby the spring-catch can be withdrawn to release the hinged 85 bar by turning the said handle, as set forth.

ORLANDO TISDEL GRATTAN.
